UNITED STATES PATENT OFFICE.

CHARLES H. LEWIS, OF WHITE EARTH, NORTH DAKOTA.

NECK-YOKE HOLDER FOR WAGON-TONGUES.

960,566.

Specification of Letters Patent. Patented June 7, 1910.

Application filed October 30, 1909. Serial No. 525,569.

To all whom it may concern:

Be it known that I, CHARLES H. LEWIS, a citizen of the United States, residing at White Earth, in the county of Montraille 5 and State of North Dakota, have invented certain new and useful Improvements in Neck-Yoke Holders for Wagon-Tongues, of which the following is a specification.

This invention relates to neck yoke holders 10 for wagon tongues, and relates more particularly to spring clipped holders which are adapted to receive the neck yoke ring and maintain the same against accidental removal from the tongue.

15 The object of this invention is to produce a neck yoke holder of this class which while serving the purpose of securely holding the neck yoke against removal from the tongue is also adapted to hold the neck yoke for 20 easy removal.

It is further intended to construct a device of this character which while adequately serving the above purpose, is simply and strongly constructed.

25 With these and further objects which will hereinafter appear, my invention will now be fully set forth and described, reference being had to the accompanying drawings, which form a part of this specification, and 30 in which,

Figure 1 is a side elevation of my improved device as applied to the end of a wagon tongue, and Fig. 2 is a bottom view of the device.

35 Referring more particularly to said drawings, 1 indicates the wagon tongue, having the usual clip 2 overlying the top of the tongue, and being turned downwardly and backwardly to engage the lower side of the 40 tongue. In the construction shown, said clip 2 is provided at its lower portion 3 with an offset 4, spaced from the tongue, and provided adjacent the bend thereof with a longitudinal slot 5 extending from said bend 45 toward the end of said offset 4.

Inclosing the tongue 1 and the clip 2 near the end of said tongue, is a band or yoke 6, said band or yoke lying over said tongue and extending downwardly against the sides 50 thereof, and having its ends occurring oppositely and bored at 7 to provide bearings for a pivoted arm 8. Said arm comprises a hook member 9, the bearing portion 10, and a loop 11 formed at the rear end of said arm 55 8 and extending upwardly to surround and operate vertically around said tongue 1.

Said loop 11, as shown in the present embodiment is or may be formed as a continuation of the arm, and is bent into the elongated loop form shown. Said hook 60 member 9 is bent upwardly and backwardly, and has its free end normally projected into said slot 5. Secured between said offset 4, and the lower side of the tongue 1 is the end of a spring 12. Said spring projects rearwardly, and has its rear end 13 bent downwardly and apertured to inclose the intermediate portion of said arm 8, which is permitted to slide therethrough. Said spring 12 bears downwardly on said arm 8, and 65 tends to normally maintain the hook member 9 in its position within the slot 5. When the loop 11 is drawn upwardly, and arm 8 is drawn toward the tongue 1 against the tension of spring 12, said hook 9 is withdrawn from the aperture or slot 5, permitting the passage of a neck yoke ring *a* over the tip of tongue 1 and behind hook 9. Release of the loop 11 permits the return of hook 9 to its normal position, in which position it locks said ring *a* in position on the tip of the tongue. 70

It is evident from the above, that my improved device is a simple, serviceable and durable holder for neck yoke rings, and one 80 which is applicable to any wagon tongue at present in use.

Having thus described my invention what I claim and desire to secure by Letters Patent of the United States, is:—

1. A neck yoke holder, comprising in combination with a tongue, a clip having an offset secured to said tongue, said offset having a longitudinal slot formed therein, a yoke inclosing said tongue and having a depending bearing, an arm having a hook journaled in said bearing, the free end of said hook projecting into said slot, a spring secured between said tongue and said offset and maintaining said hook normally projected 95 into said slot, and a loop formed on the rear end of said arm and inclosing said tongue whereby said arm may be rocked to open said hook. 100

2. A neck yoke holder, comprising in combination with a tongue, a clip having an offset secured to said tongue, said offset having a longitudinal slot formed therein, a yoke inclosing said tongue and having a depending bearing, an arm having a hook journaled 110 in said bearing, the free end of said hook projecting into said slot, a spring secured

between said tongue and said offset and having an end slidably engaging said arm, and a loop formed on the rear end of said arm and inclosing said tongue whereby said arm 5 may be rocked to open said hook.

3. A neck yoke holder, comprising in combination with a tongue, a clip overlying the top of the tongue and being turned downwardly and rearwardly to engage the lower 10 side of the tongue, being offset from the tongue at its free lower end and provided adjacent the bend formed by the offset portion with a longitudinal slot, a pivoted arm

supported from the tongue and having a hook member the free end of which normally 15 projects in said slot, and a spring having one end engaging between the offset portion of the clip and the under side of the tongue, and having its opposite end engaging the pivoted arm. 20

In testimony whereof I affix my signature in presence of two witnesses.

CHARLES H. LEWIS.
